CLAIM

The ornamental design for a hair dryer, as shown and described.

DESCRIPTION

FIG. 1 is a perspective view of my new design, showing a hair dryer;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof; and,

FIG. 9 is a perspective exploded view thereof.

The line shading in FIGS. 1-9 represents contour and not surface ornamentation.

The broken lines shown in the figures illustrate portions of the hair dryer which form no part of the claimed design.
